CLAIM

The ornamental design for a postcard, as shown and described.

DESCRIPTION

FIG. 1 is a perspective view of a postcard in a partially peeled configuration, showing my new design;

FIG. 2 is a perspective view thereof in an un-peeled configuration;

FIG. 3 is a top plan view thereof;

FIG. 4 is a bottom plan view thereof;

FIG. 5 is a left elevation view thereof;

FIG. 6 is a right elevation view thereof;

FIG. 7 is a front elevation view thereof;

FIG. 8 is a rear elevation view thereof;

FIG. 9 is a perspective view of a second embodiment of the postcard in a partially peeled configuration;

FIG. 10 is a perspective view of the embodiment of FIG. 9 in an un-peeled configuration;

FIG. 11 is a top plan view of the embodiment of FIG. 10;

FIG. 12 is a bottom plan view of the embodiment of FIG. 10;

FIG. 13 is a left elevation view of the embodiment of FIG. 10;

FIG. 14 is a right elevation view of the embodiment of FIG. 10;

FIG. 15 is a front elevation view of the embodiment of FIG. 10;

FIG. 16 is a rear elevation view of the embodiment of FIG. 10;

FIG. 17 is a perspective view of a third embodiment of the postcard in a partially peeled configuration;

FIG. 18 is a perspective view of the embodiment of FIG. 17 in an un-peeled configuration;
FIG. 19 is a top plan view of the embodiment of FIG. 18;
FIG. 20 is a bottom plan view of the embodiment of FIG. 18;
FIG. 21 is a left elevation view of the embodiment of FIG. 18;
FIG. 22 is a right elevation view of the embodiment of FIG. 18;
FIG. 23 is a front elevation view of the embodiment of FIG. 18;
FIG. 24 is a rear elevation view of the embodiment of FIG. 18;
FIG. 25 is a perspective view of a fourth embodiment of the postcard in a partially peeled configuration;
FIG. 26 is a perspective view of the embodiment of FIG. 25 in an un-peeled configuration;
FIG. 27 is a top plan view of the embodiment of FIG. 26;
FIG. 28 is a bottom plan view of the embodiment of FIG. 26;
FIG. 29 is a left elevation view of the embodiment of FIG. 26;
FIG. 30 is a right elevation view of the embodiment of FIG. 26;
FIG. 31 is a front elevation view of the embodiment of FIG. 26;
FIG. 32 is a rear elevation view of the embodiment of FIG. 26;
FIG. 33 is a perspective view of a fifth embodiment of the postcard in a partially peeled configuration;
FIG. 34 is a perspective view of the embodiment of FIG. 33 in an un-peeled configuration;
FIG. 35 is a top plan view of the embodiment of FIG. 34;
FIG. 36 is a bottom plan view of the embodiment of FIG. 34;
FIG. 37 is a left elevation view of the embodiment of FIG. 34;
FIG. 38 is a right elevation view of the embodiment of FIG. 34;
FIG. 39 is a front elevation view of the embodiment of FIG. 34;
FIG. 40 is a rear elevation view of the embodiment of FIG. 34;
FIG. 41 is a perspective view of a sixth embodiment of the postcard in a partially peeled configuration;
FIG. 42 is a perspective view of the embodiment of FIG. 41 in an un-peeled configuration;

FIG. 43 is a top plan view of the embodiment of FIG. 42;
FIG. 44 is a bottom plan view of the embodiment of FIG. 42;
FIG. 45 is a left elevation view of the embodiment of FIG. 42;
FIG. 46 is a right elevation view of the embodiment of FIG. 42;
FIG. 47 is a front elevation view of the embodiment of FIG. 42;
FIG. 48 is a rear elevation view of the embodiment of FIG. 42;
FIG. 49 is a perspective view of a seventh embodiment of the postcard in a partially peeled configuration;
FIG. 50 is a perspective view of the embodiment of FIG. 49 in an un-peeled configuration;
FIG. 51 is a top plan view of the embodiment of FIG. 50;
FIG. 52 is a bottom plan view of the embodiment of FIG. 50;
FIG. 53 is a left elevation view of the embodiment of FIG. 50;
FIG. 54 is a right elevation view of the embodiment of FIG. 50;
FIG. 55 is a front elevation view of the embodiment of FIG. 50; and,
FIG. 56 is a rear elevation view of the embodiment of FIG. 50.
The dash-dot lines shown in FIGS. 1-3, 6, 7, 9-11, 14, 15, 17-19, 22, 23, 33-35, 38-43, 45, 47, 49-51, and 54-55 indicate that the edge of the postcard has no specific length.
The arrows shown in dashed lines in FIGS. 18-19, 34-35, 42-43, and 50-51 represent portions of the article that form no part of the claimed design.
The arrows shown in FIGS. 10, 11, 18, 19, 26, 27, 34, 35, 42, 43, 50, and 51 are a part of the claimed design and do not show a direction of movement.
The shade lines shown in FIGS. 1-56 show surface contour and form no part of the claimed design.
The process of peeling the postcard forms no part of the claimed design.
The postcard according to the claimed design may be any color or combination of colors.
